Primary Examiner — Elizabeth J Oswecki(74) *Attorney, Agent, or Firm* — Muncy, Geissler, Olds & Lowe, P.C.(57) **CLAIM**

The ornamental design for a tree stand, as shown and described.

DESCRIPTION

FIG. 1 is a Top Perspective view of a tree stand showing my new design;

FIG. 2 is a Bottom Perspective view thereof;

FIG. 3 is a Front elevational view thereof;

FIG. 4 is a Rear elevational view thereof;

FIG. 5 is a Right side elevational view thereof;

FIG. 6 is a Left side elevational view thereof;

FIG. 7 is a Top plan view thereof; and,

FIG. 8 is a Bottom plan view thereof.

The broken lines shown in the drawings represent portions of the tree stand that form no part of the claimed design.

1 Claim, 6 Drawing Sheets(56)
